(57) CLAIM

The ornamental design for a security porch light, as shown and described.

DESCRIPTION

FIG. 1 is a top, front, right side isometric view of a security porch light embodying my new design;

FIG. 2 is a top view thereof;

FIG. 3 is a right side view thereof, the left side view being identical thereto; and,

FIG. 4 is a front view thereof, the rear view being identical thereto.

The design of the bottom of the security porch light is not being claimed.
